(57) **CLAIM**

The ornamental design for a dowel, as shown and described.

DESCRIPTION

FIG. 1 is a perspective view of one embodiment of the dowel of the subject invention.

FIG. 2 is a front plan view of the dowel of FIG. 1.

FIG. 3 is a left side plan view of the dowel of FIG. 1, the opposite side being substantially a mirror image thereof.

FIG. 4 is a rear plan view of the dowel of FIG. 1, the opposite side being a mirror image thereof.

FIG. 5 is a top plan view of the dowel of FIG. 1.

FIG. 6 is a bottom plan view of the dowel of FIG. 1.

FIG. 7 is a perspective view of a second embodiment of the subject invention.

FIG. 8 is a front plan view of the dowel of FIG. 7.

FIG. 9 is a left side view of the dowel of FIG. 7, the opposite side being a mirror image thereof.

FIG. 10 is a front plan view of the dowel of FIG. 7.

FIG. 11 is a top plan view of the dowel of FIG. 7; and, FIG. 12 is a bottom plan view of the dowel of FIG. 7.
